UNITED STATES PATENT OFFICE

FRANCIS DEANE, OF FOLLOWFIELD, ENGLAND

MEANS FOR REPRODUCING SOUND FROM PHOTOGRAPHIC RECORDS

Application filed December 7, 1932, Serial No. 646,147, and in Great Britain May 7, 1931.

The invention relates to improvements in and connected with the reproduction of sound in talking cinematography. It is known in this class of work to form on a film 5 two separate sound tracks and to employ separate sources of light and separate light sensitive cells for the tracks so that one cell can deal with the low frequency side and the other with the high frequency side. It 10 is also known to employ a single source of light for two light sensitive cells connected to a common amplifier so that both cells have the same response but if one fails the other will enable the apparatus to continue. Still further it is also known to employ a common light source for two separate sound tracks and to split the light into two pencils by means of prisms so that two 15 separate amplifiers are employed each having its own thermionic circuit. The object of my present invention is to simplify sound reproduction and the invention is characterized by a common source of light for two light sensitive cells and means between 20 the sound track and the light sensitive cells for dividing the light into two zones so that the same image is directed on to both light sensitive cells each cell being connected to a separate loud speaker through its own 25 thermionic circuit, the loud speaker appropriate to one cell however being tuned to respond to high frequency notes, and the other to low frequency notes.

My invention will be more clearly understood by reference to the accompanying diagram in which a selenium cell 1 is separated from a photo-electric cell 2 by a thin opaque partition 3 having a knife edge 4. The selenium cell 1 is connected to its own 35 loud speaker 5 through its own thermionic circuit 6, the loud speaker 5 being tuned to respond to high frequency notes. The photo-electric cell is connected to its own loud speaker 7 through its own thermionic 40 circuit 8, this loud speaker 7 being tuned to respond to low frequency notes.

The film is indicated by the reference numeral 9 and its sound track area by its reference numeral 10. A small aperture 11 50 in a suitable box 12 is in juxtaposition to

the edge 4 so that the knife edge 4 divides the beam of light from a source 13 into two equal parts, the angles of incidence of these two beams being small and so directed that they are most effectively projected on to the 55 cells 1 and 2. The usual supplementary slotted plate 14 can be located in front of the aperture 11.

By means of the present invention full range of sounds as recorded on a single 60 sound track are reproduced as there is no necessity as at present with single sound track an amplifier circuits to strike a medium between high and low frequency sounds.

What I claim is:—

In means for reproducing sounds from photographic records two light sensitive cells, a common source of light for said two light sensitive cells and means between the 70 sound track and the light sensitive cells for dividing the light into two zones so that the same image is directed on to both light sensitive cells, a separate loud speaker for each said light sensitive cell and each said light 75 sensitive cell being connected to its separate loud speaker through its own thermionic circuit the loud speaker appropriate to one cell being tuned to respond to high frequency notes and the other to low frequency 80 notes.

In witness hereof I have signed this specification.

FRANCIS DEANE.
